UNITED STATES PATENT OFFICE.

GEORG RITTER, OF STUTTGART, GERMANY.

TELEPHONE SYSTEM.

SPECIFICATION forming part of Letters Patent No. 691,665, dated January 21, 1902.

Original application filed August 16, 1898, Serial No. 688,683. Divided and this application filed July 18, 1901. Serial No. 68,812. (No model.)

To all whom it may concern:

Be it known that I, GEORG RITTER, a citizen of the Empire of Germany, residing at Stuttgart, in the Empire of Germany, have invented certain new and useful Improvements in Telephone Systems; and I do hereby declare the following to be a full, clear, and exact description of the invention, such as will enable others skilled in the art to which it appertains to make and use the same.

This application is a division from my application, Serial No. 688,683, filed August 16, 1898.

This invention relates to an improvement in telephone systems, and in particular to a register and testing system for telephone-exchanges.

One of the objects of my invention is to provide a register system whereby the registration of a conversation chargeable against a substation will only be made when a conversation actually takes place between the person at the calling substation and another person at the substation called, as contradistinguished from those register systems in which a registration is made even where the calling subscriber is unable to obtain a reply from the called substation.

A further object of my invention is to provide means for testing the lines of a telephone plant provided with my register system.

With these general objects in view, and some others which will be obvious to those skilled in the art from the description hereinafter, my invention consists in the features, details of construction, and combinations of parts, which will first be described in connection with the accompanying drawings and then pointed out in the claims.

In the drawings, Figure 1 is a diagrammatic view of a metallic return telephone system provided with a register and testing system embodying my invention, and Fig. 2 a similar view showing two switchboards embodying my invention.

Referring first to Fig. 1 of the drawings, the Roman numerals I and II indicate two substations having the line-wires 1, 2, 3, and 4, respectively, which are connected to the jacks A A' of any desired type, located at the central station. Each line is represented at

the central-station switchboard by an annunciator of any desired kind, as indicated at B B'.

C C' represent plugs, the former being an answering-plug and the latter a calling-plug. 55 Each plug has the usual tip-and-shell terminals, as indicated at c c', respectively, arranged to coact with the respective jack-springs of the jacks into which said plugs may be inserted. In addition each plug has 60 a third terminal c², arranged to enter and fit tightly into a jack-ring arranged in front of each jack, said jack-rings being shown at D D', respectively.

The plug-terminals c' are connected by a 65 conductor 5, while the plug-terminals c are connected by an interrupted conductor having the two parts 6 7, arranged to be electrically connected through an automatic circuit-closer, which will now be described.

E is a switch-lever pivoted at e and provided with a contact-plate e', arranged to contact with an anvil e². The pivotal point e and the anvil e² form the terminals of the respective parts 6 and 7 of the interrupted plug-conductor. The said switch-lever E is provided at one end with a beveled portion arranged to coöperate with the beveled face of a nose f, formed on an armature latch-lever F, pivoted at f' and provided with an armature f², arranged to be attracted and held by an electromagnet G, whose coil has one terminal connected to an anvil g and the other terminal connected to one pole of a local battery H whose other pole is grounded. The 85 armature-lever F is provided with a contact-spring f³, arranged to engage the anvil g and close a circuit through the coils of the electromagnet G. To the armature-lever is connected a lever J, pivoted at j, the connection 90 between the two levers being made by means of a link j' of insulating material.

The levers J and F are normally drawn away from the magnet G by means of a suitable spring, as shown at j². The lever J is 95 provided with three contact-points, as shown at j³ j⁴ j⁵, the latter being arranged to coöperate with a contact device j⁶ for a purpose hereinafter described. The contact-points j³ j⁴ are arranged to engage at different times 100 either the contact-plate k or the contact-plate k', respectively, which contact-plates are fixed

on a two-armed lever K, forming part of a compound circuit-changing device, which also comprises the levers K' and K², the three levers K K' K² being connected for simultaneous movement by means of a link k³ of insulating material, which is pivoted to each of the levers K K' K².

The lever K is arranged for contact with either of the contact-points k³ or k⁴, the lever K' with either of the contacts k⁵ or k⁶, and the lever K² with either of the contacts k⁷ k⁸. The said lever K is provided with a roller k⁹, arranged to engage a projection e³, preferably in the form of a bent spring, secured by one end to the switch-lever E, whereby when the circuit-changer is moved, so as to shift the roller k⁹ to the left, said roller will engage the projection e³ and force the switch-lever into engagement with the nose f of the armature-lever. The switch-lever E is normally drawn downward by a spring e⁴.

The contact-points k⁶ and k⁸ form the terminals of the operator's telephone set, (indicated at L,) while the contact-points k⁵ and k⁷ form the terminals of the clearing-out annunciator M. The levers K' and K² are connected to the conductors 6 and 5, respectively, by the corresponding conductors 14 and 15.

The register and test circuits and instruments are as follows: The jack-rings of each line are connected by a conductor to one pole of the register-battery N, two of these conductors being indicated at 8 and 9, respectively, and each including the register for its own line, which registers are shown at O and O', respectively. The opposite terminal of the battery N is connected by a conductor 11 to the contact-point k³. That terminal c² of the answer-plug which contacts with the respective jack-ring is connected by a conductor 10 to the pivotal point of the lever J. The corresponding terminal c² of the calling-plug is connected by a conductor 12 to the battery N and by branches 12^a and 12^b to the contact-point k⁴ and the contact device j⁶, respectively, a high resistance, preferably a condenser P, being included in the conductor 12 between the battery N and the branch conductors 12^a and 12^b. One terminal of the operator's telephone set is connected by a conductor 13 to the same pole of the register-battery N to which are connected the conductors 8 and 9.

A suitable source of calling-current is provided, as shown at Q, which is connected to any suitable calling-key for closing said source onto the plug-conductor cords of the calling-plug, said calling-key being indicated at R.

At each substation the usual telephone instruments are provided, and in addition means for grounding one of the substation-lines is supplied. This is done, preferably, by providing at each station a grounded branch 16 17, each ending at a contact-point s s', over which the telephone hook-lever S S' may pass when the receiver is removed from

said hook, thereby momentarily grounding that substation-line which is connected at one end to the pivotal point of the respective hook-lever S S' and at the other end to the tip-terminals c' of the inserted plug.

The operation of the apparatus is as follows: Assuming that station I desires to communicate with station II and has called the central station in the usual way, the operator inserts the answer-plug C in the jack of the line to station I and moves the compound circuit-changer in such a way that levers K² and K' are on the contact-points k⁸ and k⁶, respectively, whereby the central-station telephone set is put in circuit with the substation I over the line-wires 1 and 2, the plug-connector conductors 5 and 6, the branch wires 14 and 15, the levers K' and K², contact-points k⁶ and k⁸, and the operator's set. Upon receiving the number of the station desired the operator then inserts the corresponding calling-plug in the proper jack of the line to the desired station (in this case assumed as station II) and then moves the compound circuit-changer so that its levers K² and K' are brought upon the contacts k⁷ and k⁵, respectively, thus cutting out the operator's telephone-set L and cutting in the clearing-out annunciator M. This movement of the circuit-changer causes the lever K to bring its roller k⁹ into engagement with the projection e³, thereby forcing the end of the switch-lever E into engagement with the nose f of the armature-lever F, whereby the two parts 6 and 7 of the plug-conductor are disconnected, and the latter conductor 7 is closed onto the battery H through the switch-lever E, the armature-lever F, the contact-spring f³, the anvil g, and the coil of the electromagnet G. At the same time the lever J is forced to one side by means of its connection with the armature-lever, and thereby the contact-point j³ is brought against the contact device j⁶ for a purpose hereinafter described in connection with the description of the testing-circuit. Immediately upon moving the circuit-changer, as just described, the operator presses for a short interval the calling-key R, thus ringing the bell at the called station II, but not affecting the bell at the calling station I, because the circuit back to the latter station is interrupted between the switch-lever E and the contact point or anvil e². If now the called subscriber answers the call by removing his telephone-receiver from its hook S', the latter in moving upward passes over and momentarily contacts with the contact-point s', thereby grounding his station-line 3 momentarily and energizing the magnet G, the circuit being as follows: from the terminal of battery H over the coils of the electromagnet G, the anvil g, the spring f³, armature-lever F, switch-lever E, conductor 7, through the respective plug-terminal and jack-spring to the line 3, along the same to the hook-lever S', thence by contact-point s' to the ground and back to the battery H through the grounded

- terminal of the latter. The electromagnet G being thus energized, draws the armature-lever F to one side, and thus releases its nose f from the end of the switch-lever E, the latter being then drawn down by its spring e^4 , whereby the circuit through the electromagnet is broken by the separation of the levers E and F, and the talking-circuit is closed across the parts 6 and 7 of the plug-conductor 10 by the lever E coming into contact with the anvil e^2 and the armature-lever F being drawn to one side by the spring j^2 , so as to break the contact between the spring f^3 and the anvil g . The talking-circuit will be as follows: 15 from station I over the lines 1 and 2, across the plug-circuits (one limb of which is formed by the conductor 5 and the other by the parts 6 and 7, the lever E, and anvil e^2) along the lines 3 and 4 to the instruments at station II. 20 The failure of electromagnet G to move its armature-lever F and release the switch-lever E within a short interval after a call has been sent out to a called substation will indicate to the operator that the called subscriber has 25 not answered his telephone call, whereupon either another call may be sent over the said line or the calling subscriber may be notified and the connections cleared out. Upon the completion of a conversation between sub- 30 scribes and the ringing-off of either of them the clearing-out annunciator will be dropped and the central station thereby notified, whereupon the operator withdraws the plugs from the jacks. 35 The manner of operation of the register is as follows: When the answer-plug C is inserted in a jack, the terminal c^3 of said plug is in contact with the ring D and the register-circuit is closed at the jack, but is still open 40 at one other point and at only said other point, this open or interrupted circuit being as follows: from the contact-point k^3 , over the conductor 11, to the positive pole of the register-battery N, thence along conductor 9, 45 through the magnet of the register O, to the jack-ring D, over the terminal c^2 of the answer-plug, along conductor 10 to the pivotal point of the lever J, and thence to the contact-point j^4 of said lever. In this description 50 it is assumed that the operator has first moved his circuit-changer so as to include his telephone L in the talking-circuit before inserting the plug C, which is the form of procedure hereinabove described with relation to 55 the talking-circuit. Therefore it will be clear that before inserting the answer-plug into its respective socket the register-circuit will be open at two points only—viz., between the jack-ring and the terminal c^2 of the answer- 60 plug C and between the contact-point k^3 and the point j^4 of the lever J. The former opening is closed upon the insertion of the answer-plug C on answering the call of the subscriber; but the other opening remains open 65 during all the operations of making a connection and up to the time the called subscriber removes his telephone from the hook to answer his call, or, in other words, until the electromagnet G is energized, as has previously been described, at which time the 70 switch-lever E is released, thus breaking the circuit of the electromagnet G and allowing the armature-lever F to fly back and move the lever J with itself. This movement brings the contact-point j^4 of the lever J into contact 75 with the contact-plate k' of the lever K, and as the latter is at that time upon the contact-point k^3 the second opening of the register-circuit is closed and the register operated. Furthermore, the register-circuit remains 80 closed until the operator removes the answer-plug from the jack upon the completion of the conversation, whereby it is possible not only to use a register which will tally the number of conversations actually had by the calling-line, but, if desired, to employ a register which will record the duration of such conversations, the latter form of register being especially applicable in those systems where the use of the instruments is charged for according to the duration of such use. Such a register is shown at O in connection with the conductor 9, while a register which merely tallies the number of conversations, irrespective of their duration, is indicated at O' as included in the conductor 8. 85 90 95
- From the above it is clear that the register device tallies only the conversations that are had by a calling substation, and no registration is made of any mere attempts to call a subscriber. 100
- The test-circuits and the manner of making a test will now be described, reference being made to Fig. 2 of the drawings. In this figure two substations are shown at I and II, respectively, and the central exchange is indicated as provided with two switchboards and instruments therefor, one at the right hand and one at the left. The latter switchboard is shown with its instruments in the same position as those in Fig. 1, while the right-hand switchboard has its instruments in the position in which they would be after answering a call of the subscriber and when testing a line before making the desired connection, it 105 being assumed in this case that the line being tested is the one to station II, which is shown as already in use, being connected to station I through the left-hand switchboard, as already described in connection with Fig. 110 115 120 125
1. The substation-circuits from the substation which is supposed to have called the operator at the right-hand switchboard and the calling-drop therefor have been omitted to avoid confusion.
- It will be noted that the register-circuit battery N and the condenser P are common to both switchboards. Separate sources of calling-current Q Q' are shown for each switchboard for the purpose of avoiding the confusion of circuits; but it is obvious that only one such a source need be used. It will now be assumed that the operator at the right-hand switchboard has received a call and has 130

moved the compound circuit-closer so as to include the respective operator's telephone L' in the talking-circuit of the calling station. The number of the desired station being 5 known and assumed to be that of station II, (whose line is supposed to be then in use,) the operator takes up the corresponding calling-plug C² and with its tip-terminal touches the jack-ring D² of the line to station II, 10 which ring represents said line in the right-hand switchboard. At the same time the operator listens at the receiver of the telephone set and, owing to the closing of the test-circuit by the contact of the tip-terminal 15 and the jack-ring, a "click" is heard in the said receiver, whereby the operator is informed that said line to station II is then in use.

The testing-circuit is as follows: from one 20 terminal of the condenser P along the conductor 12 to the jack-ring D', then along the conductor 8^a to the corresponding jack-ring D², and from there over the tip-terminal of the plug C², over the conductor 7^a (which 25 corresponds in all respects to the conductor 7 of Fig. 1) to the pivotal point of the switch-lever E', along the same to the contact-anvil e²², thence over a part of the conductor 6^a and conductor 15^a to the circuit-closer lever K¹¹, 30 from there through the contact-point k⁶⁶, through the operator's telephone set L' and conductor 13^a to the terminal of the battery N, and from the other terminal of said battery back to the opposite side of the condenser 35 or other high resistance P. Of course the condenser prevents the current from flowing over said circuit; but the charging and discharging of said condenser will produce the necessary sound in the operator's telephone in 40 order to give warning that the tested line is in use. It is obvious that if the line to station II was not in use and the plug C' not in the jack D' then the testing-circuit would not be complete and the condenser could not be charged 45 by touching the tip-terminal of plug C² against the corresponding jack-ring D².

It will be observed that the conductor 12 of the plug C' is in connection with one pole of the battery N, (over the condenser P,) and it 50 is to be noted that if the corresponding conductor 10 of the answer-plug C is also maintained in connection with the same terminal of the battery N the testing of the jack-ring D³ of the line to station I while said line is in use 55 will also result in producing a sound in the telephone-receiver of the operator making the test. It is one of the functions of the lever J, its points j³ j⁵, and conductors 12^a and 12^b to assist in maintaining this connection of the 60 conductor 10 of the answer-plug with said terminal of the battery N. For example, when the operator at the left-hand switchboard, Fig. 2, receives a call—for example, from station I—and moves the circuit-changer to bring the 65 operator's telephone L into the talking-circuit and then inserts the answer-plug in the respective jack D then the lever K will be on

the contact-point k⁴ and the contact-point j³ of the lever J will be in contact with the plate k on the lever K, whereby the conductor 10 70 of the said answer-plug will be in connection with the desired terminal of the battery N through the lever J, lever K, conductor 12^a, and conductor 12. When the operator at said left-hand switchboard has moved the 75 circuit-changer so as to include the clearing-out drop in the talking-circuit, (as a loop or bridge therein,) the lever K will rest on the contact-point k³, as shown in Fig. 1, and the connection between said lever K and the contact-point j⁵ of the lever J will be broken; but at this time the lever J has been moved so as to bring its contact-point j⁵ into engagement with the contact device j⁶, as has been described hereinbefore, and thus the connection 80 of the conductor 10 with the desired terminal of the battery N is still preserved through the lever J, contact device j⁶, branch conductor 12^b, and conductor 12. Furthermore, when the armature-lever F has been 85 released from the switch-lever E and drawn to the left by the spring j², as has been hereinbefore described, and the lever J has thereby been moved to close the register-circuit through its contact-point j⁴ and the contact- 90 plate k' on the lever K the conductor 10 is still maintained in connection with the desired terminal of the battery N over the lever J, the lever K, and conductor 11, the said lever J, lever K, and conductor 11 thus forming 95 not only a part of the register-circuit, but also acting as a part of the test-circuit in case at this time any test should be made of the jacks of the line to the calling-station, (station I.) Of course while this connection exists 100 the condenser P is not in the testing-circuit; but this is immaterial, since the telephone-receiver of the operator making the test will be operated by the current actually flowing over the test-circuit at the time of 105 making the test, and thereby said operator will be warned that the line to station I is in use.

From the above description it will be noted that the talking-circuit is kept entirely independent of the register and testing circuits 115 and that no magnets or the like are included in the talking-circuit for actuating the register, but that the magnet G, which performs this function, is in a branch from the talking- 120 circuit and that there is no circuit through the said branch while the talking-circuit is in use, the circuit being closed only momentarily and prior to the closing of the talking-circuit.

Having thus fully described my invention, what I claim as new, and desire to secure by Letters Patent of the United States, is—

1. In a telephone system, the combination with a plurality of substation-conductors, and connector-conductors for completing the connections between said substation-conductors, whereby a talking-circuit is completed, of a branch circuit leading from said talking-cir- 125

cuit, means for closing the same, a register-circuit, and means operated by the closing of the branch circuit and arranged to close the register-circuit.

5 2. In a telephone system, the combination with a plurality of substation-conductors and connector-conductors for completing the connection between said substation-conductors, whereby a talking-circuit is completed, of a 10 branch circuit leading from said talking-circuit, means at the called substation for closing the branch circuit, a register-circuit and means operated by the closing of the branch circuit and arranged to close the register-circuit.

15 3. In a telephone system, the combination with a plurality of substation-conductors and connector-conductors for completing the connection between said substation-conductors, whereby a talking-circuit is completed, of a 20 branch circuit leading from said talking-circuit, a register-circuit, electromagnetic means included in the branch circuit and arranged to close the register-circuit, and means for 25 closing said branch circuit.

4. In a telephone system, the combination with a plurality of substation-conductors and connector-conductors for completing the connection between said substation-conductors 30 whereby a talking-circuit is completed, of a branch circuit leading from one of the said connector-conductors, means at the called substation for closing the branch circuit, a register-circuit, and electromagnetic means 35 located in the branch circuit and arranged to close the register-circuit.

5. In a telephone system, the combination with a plurality of substation-conductors and connector-conductors for completing the connection between said substation-conductors, whereby a talking-circuit is completed, of a 40 grounded branch circuit leading from the talking-circuit, a register-circuit, electromagnetic means in said branch circuit arranged to close the register-circuit, and means at the 45 called substation for grounding one of the substation-conductors, whereby the branch circuit is closed.

6. In a telephone system, the combination with a plurality of substation-conductors and connector-conductors for completing the connection between said substation-conductors, whereby a talking-circuit is completed, of a 50 register-circuit, a grounded branch circuit leading from one of the connector-conductors, an electromagnetic circuit-closer having its coils included in said branch circuit and arranged to close the register-circuit, and means at the called substation for closing said branch 55 circuit.

7. In a telephone system, the combination with a plurality of substation-conductors and connector-conductors for completing the connection between said substation-conductors, whereby a talking-circuit is completed, of a 60 register-circuit, a grounded branch conductor connected to one of the connector-con-

ductors, an electromagnetic circuit-closer having its coils included in the said grounded branch conductor, said circuit-closer being 70 arranged to close the register-circuit, a grounded branch conductor at the called substation, and means for closing said substation branch onto the substation-line.

8. In a telephone system, the combination with a plurality of substation-conductors and connector-conductors for completing the connection between said substation-conductors, whereby a talking-circuit is completed, of a 75 register-circuit, a branch circuit leading from 80 said talking-circuit, means operated by the closure of said branch circuit and arranged to close the register-circuit, and a telephone hook-lever at the called station arranged to momentarily close the branch circuit when 85 moving upward.

9. In a telephone system, the combination with a plurality of substation-conductors, jacks associated therewith, of a register-circuit normally open at the jacks and at another point, plugs and connector-conductors arranged to enter the respective jacks, one of said plugs being arranged to close the register-circuit at the jack into which it is inserted, and one of said connector-conductors 90 being interrupted, of a branch circuit leading from the interrupted connector-conductor, electromagnetic means included in the branch circuit and arranged to close both the register-circuit at the second point where it is 95 open and the interrupted connector-conductor, and means for closing the branch circuit.

10. In a telephone system, the combination, with the substation-lines, the jacks associated therewith, the plugs for insertions in 105 said jacks and the plug connector-conductors, one of which is interrupted, of a switch device arranged to close said interruption of the said connector-conductor, a register-circuit open at the jacks and at another point 110 and arranged to be closed at the jack by the insertion of one of said plugs therein, means for closing the register-circuit at the other point, said means being held open by the switch device when the latter is in its open 115 position, retaining mechanism for holding said switch-lever in its open position, and means operated by a called substation for releasing said retaining mechanism, whereby the switch-lever closes its connector-conductor and the means for closing the register-circuit is released to close the same.

11. In a telephone system, the combination, with a plurality of substation-conductors, and connector-conductors for completing the connection between said substation-conductors, whereby a talking-circuit is completed, of a 125 branch circuit leading from the said talking-circuit and normally open at the central station and at one of the substations, a register-circuit, means for closing the register-circuit, said means being operated by the closing of the branch circuit, means operated at the central station in making connections be-

tween substations for closing the opening at that place in the branch circuit, and means operated by the subscriber at the called station for closing the branch circuit at that 5 point.

12. In a telephone system, the combination, with a plurality of substation-conductors, and connector-conductors for completing the connections between said substation-conductors, 10 one of said connector-conductors being interrupted, of a register-circuit open at two points, means operated in making connections at the central station for closing the register-circuit at one of said points, and means operated by 15 the called subscriber for closing the interrupted connector-conductor and for closing the register-circuit at the other point where it is open.

13. In a telephone system, the combination, 20 with a plurality of substation-conductors, and connector-conductors for completing the connections between said substation-conductors, whereby a talking-circuit is completed, of a branch circuit, a register-circuit, means at the 25 central station for closing the branch circuit onto the talking-circuit, means at the called substation also for closing the branch circuit onto the talking-circuit, and mechanism operated by the closing, at the called substation, 30 of the branch circuit onto the talking-circuit for closing the register-circuit and again opening the branch circuit.

14. In a telephone system, the combination with a jack, a register-circuit open at the jack 35 and at a second point, a register included in said circuit, a plug insertible in the jack and arranged to close the register-circuit at that point, a talking-circuit including the plug and jack, and a switch arranged to close the 40 talking-circuit and the register-circuit at the

second point, of mechanism for holding the said switch open, an electromagnet arranged to release the switch from said holding mechanism, means operated in completing the connection between substations for engaging the 45 switch with its holding mechanism, and means included in the talking-circuit for actuating the electromagnet to release the switch, whereby the talking-circuit and the register-circuits are closed.

15. In a telephone-exchange, the combination with a register device, a register-circuit including the register device and the corresponding jacks, of the exchange-plugs provided with means included in the register-circuit for insertion into the respective jacks, whereby the register-circuit is closed at the jacks, a testing-circuit in parallel with the register-circuit, a condenser included in said testing-circuit, means for energizing both circuits, and means for opening and closing the register and testing circuits alternately.

16. In a telephone-exchange, the combination with a register device, a register-circuit including the register device and the corresponding jacks, of the exchange-plugs provided with means included in the register-circuit for insertion into the respective jacks, whereby the register-circuit is closed at the jacks, a testing-circuit in parallel with the register-circuit, a resistance included in said testing-circuit, means for energizing both circuits, and means for opening and closing the register and testing circuits alternately.

In testimony whereof I affix my signature 75 in presence of two witnesses.

GEORG RITTER.
